UNITED STATES PATENT OFFICE.

HUGH W. PEIGHTAL, OF DENVER, COLORADO.

FLY-SCREEN.

SPECIFICATION forming part of Letters Patent No. 767,832, dated August 16, 1904.
Application filed November 5, 1903. Serial No. 179,984. (No model.)

To all whom it may concern:

Be it known that I, HUGH W. PEIGHTAL, a citizen of the United States of America, residing in the city and county of Denver and State of Colorado, have invented certain new and useful Improvements in Fly-Screens; and I do declare the following to be a full, clear, and exact description of the invention, such as will enable others skilled in the art to which

it appertains to make and use the same, reference being had to the accompanying drawings, and to the letters of reference marked thereon, which form a part of this specification.

15 This invention relates to improvements in fly-screens, and more particularly to a metallic frame for fly-screens.

Its object is to produce a metallic fly-screen frame which is inexpensive to manufacture, 20 in which an old screen may readily be replaced without the aid of tools, is light in weight, and with which an even tension may be given to the screen.

To that end it consists of a frame made entirely of sheet metal, its various lengths being made of metal strips lapped and ribbed, forming a rigid frame, a series of screen-secur- 25 ing clips or prongs adapted to engage the screen and secure it to the frame, and a pro- 30 tecting-strip removably secured to the frame and covering the edge of the screen and its engaging points.

The invention further consists in the details of its construction and combination of its op- 35 erating parts, all of which I will now proceed to definitely describe, and then point out in the claims that which I believe to be novel.

In the drawings, Figure 1 is a face view of a screen-frame arranged according to my in- 40 vention. Fig. 2 is an enlarged detail view showing one corner of the screen-frame with screen in place. Fig. 3 is a cross-section of the frame, taken through the line 3-3 of Fig. 2.

The same reference characters indicate the 45 same parts in all the views.

Let A indicate the frame, composed of the four lengths A'. Each of these lengths A' is formed of a sheet-metal strip folded upon itself, as at A² and A³, and having the stiffen- 50 ing-ridge A⁴. (See Fig. 3.) Securing-clips

B, disposed at right angles to the length A', rest between the folds of said lengths, their inner ends being hook-shaped and protruding through elongated openings A⁵, cut in the strips A', and their outer ends protruding 55 through the orifices A⁶. These strips A' are soldered together at their ends, having lap-joints, as at A⁷.

C are the finishing or protecting strips, which are cut to fit the frame, meeting at the 60 corners in miter-joints and being secured in place by the binding-clips D. The strips C are so placed as to cover the edges of the screen and the points of its engagement with the clips B, as seen in the drawings.

In operation, the parts A' being assembled and soldered together with a rigid frame, as above described, a screen is cut to the desired size and placed over the flat face of the frame. The inner hooked ends of the securing-clips 70 B, which project through the openings A⁵, and of the strips A' are brought into engagement with the mesh of the screen E, and by grasping the outer projecting ends of the clips B the screen is drawn taut, the free ends 75 of the clips being bent over upon the frame, as shown in the drawings. After securing the screen to the frame in the manner just described the finishing-strips C are placed in position and secured to the frame by the binding-clips D.

To replace a screen, the operator has but to remove the clips D and B, which are preferably made of soft metal.

It will be seen that by engaging and secur- 85 ing the clips B at points diametrically opposite each other a tight screen of even tension is readily maintained.

Having thus described my invention, what I claim is—

1. In a fly-screen, a frame consisting of metal strips folded to form a strengthening-rib on one side, the opposite side or face being provided with transverse slots extending from the inner edge of the strips outwardly, 95 the outer edge of the frame being provided with openings between the front and rear parts of the frame and in line with the said slots, and securing-clips passed through the said openings, and having their inner extremi- 100

2
ties turned upwardly through the slots to catch the screen, their outer extremities protruding from the openings and being turned over upon the face of the frame, substantially, 5 as described.

2. In a fly-screen, a frame consisting of folded metal strips each provided with a stiffening-ridge, said strips being soldered together at their ends, and a series of engaging clips 10 removably secured in said metal strips and adapted to hold the screen in the frame, substantially as shown for the purpose stated.

3. In a fly-screen, a frame consisting of fold-

ed metal strips each provided with a stiffening-ridge, said strips being soldered together 15 at their ends, a series of engaging clips removably secured to said metal strips, and a finishing-strip of curved metal removably secured to said frame and adapted to protect the securing ends of the screen.

20 In testimony whereof I affix my signature in presence of two witnesses.

HUGH W. PEIGHTAL.
